(57) **CLAIM**

The ornamental design for an acoustic panel, as shown and described.

DESCRIPTION

FIG. 1 is a top perspective view of an acoustic panel, showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view taken at line-9 in FIG. 1;

FIG. 10 is a partial enlarged view taken at line-10 in FIG. 2;

FIG. 11 is a partial enlarged view taken at line-11 in FIG. 2;

FIG. 12 is a partial enlarged view taken at line-12 in FIG. 3;

FIG. 13 is a partial enlarged view taken at line-13 in FIG. 4;

FIG. 14 is a partial enlarged view taken at line-14 in FIG. 5;

FIG. 15 is a partial enlarged view taken at line-15 in FIG. 6;

FIG. 16 is a partial enlarged view taken at line-16 in FIG. 7; and,

FIG. 17 is a partial enlarged view taken at line-17 in FIG. 8. The broken lines in the figures are for the purposes of illustrating portions of the acoustic panel, which form no part of the claimed design.

The dash-dot-dash broken lines are for notating enlarged views, and form no part of the claim design.
